CLAIM

The ornamental design for a part of spectacle frame, as shown and described.

DESCRIPTION

1. Part of spectacle frame

The sole FIGURE is a front perspective view of part of spectacle frame showing my new design.

The parts shown by means of broken lines in the reproductions are not part of the claimed design.

The dash-dot-dash broken lines are boundary lines. It is understood that the claimed design extends to the boundary lines but the boundary lines form no part of the claimed design.
